GUN PERFORATOR

Lloyd Spencer, Los Angeles, Calif., assignor to
 Lane-Wells Company, Los Angeles, Calif., a corporation of Delaware

Application February 6, 1941, Serial No. 377,596

14 Claims. (Cl. 164—0.5)

My invention relates to gun perforators; that is, to devices which are lowered into a well casing and caused to fire bullets through the casing to permit inflow of fluids. Among the objects of my invention are:

First, to provide a gun perforator which comprises a plurality of separable gun units which are adapted to be stacked and secured end to end;

Second, to provide a sectional multiple unit gun perforator wherein each gun unit is complete in itself in that it comprises a gun bore and cartridge socket which may be loaded before being assembled with other gun units;

Third, to provide a sectional gun perforator in which the gun sections or units are particularly simple and economical of manufacture, and any one of the gun units may be readily removed and replaced in the event it should become damaged;

Fourth, to provide a gun perforator in which the axial length of each gun unit is minimized so that a maximum number of units may be incorporated in a gun of given length and weight; and

Fifth, to provide a gun perforator which is adapted to be fired electrically and which incorporates a novel arrangement for electrically connecting the gun units individually with a source of electrical energy.

With the above and other objects in view, as may appear hereinafter, reference is made to the accompanying drawing, in which:

Figure 1 is an elevational view of my gun perforator;

Figure 2 is an end elevational view of one of the gun units;

Figure 3 is a sectional view through 3—3 of Figure 2, showing two of the gun units and the manner in which they fit;

Figure 4 is an enlarged sectional view through 4—4 of Figure 3, showing the electrical connection between the conductor cable and cartridge; and

Figure 5 is an enlarged cross sectional view through 5—5 of Figure 4, showing the conductor cable and surrounding parts of the gun unit.

My gun perforator includes a plurality of gun units. Each gun unit 1 is in the form of a cylindrical disk or block which is divided diametrically into a breech portion 2 and a barrel portion 3 which are, therefore, semi-cylindrical. The breech portion 2 has greater axial length than the barrel portion and therefore extends above and below the upper and lower sides of the bar-

rel portion to form steps or shoulders 4. The upper and lower corners of the barrel portion, which are extended from the steps 4, are provided with axially directed ribs 5 having faces which are parallel to the steps 4. Complementary recesses 6 are provided in the corners of the breech portion 2. The breech and barrel portions are so proportioned that the breech end of one gun unit is adapted to fit upon the barrel portion of an adjacent gun unit, as shown best in Figures 1 and 3, the steps, ribs and recesses interlocking.

The barrel 3 is provided with a diametrically extending gun bore 7 disposed at right angles to the plane of the steps 4. The gun bore 7 extends into the breech portion 2 and is intersected by a vertically extending cartridge bore or socket 8 which extends past the gun bore but is opened to only one end of the breech portion.

20 The gun bore 7 receives a bullet 9 which is covered with a sealing plug 10 formed of soft material, but capable of preventing the entrance of well fluid.

The cartridge bore 8 receives a cartridge 11. 25 The cartridge is, for the purposes of this application, conventional and comprises a shell of Celuloid or analogous material filled with an explosive. An electrically responsive fuse which includes a contact clip 13 is provided in the upper end of the cartridge. The outer end of the cartridge bore is slightly counterbored and receives a sealing plug 14. The sealing plug comprises a relatively heavy base portion 15 and a skirt or rim portion 16. The center of the base 30 15 is provided with a contact 17 adapted to engage the contact clip 13.

Formed integrally with or secured to the base portion of the sealing plug 14 is a circular gasket 18 of larger diameter than the plug. The gasket 40 18 includes a conductor tongue 19 extending radially therefrom and terminating in a contact 20, which will be described in more detail hereinafter. The gasket, as well as the surfaces of the sealing plug 14 which would otherwise contact the gun unit, is covered with a thin but tough insulation 21. Both the gasket and insulation material are made as thin as possible. The skirt or rim of the sealing plug spreads outwardly when the explosive cartridge is discharged to prevent any flow of gases around the plug and therefore localizes the pressure area between the gun units to the diameter of the sealing plug 14.

On either side of the cartridge bore 8 the breech portion 2 is provided with threaded sockets 22 and, similarly, on either side of the gun

bore the barrel 3 is provided with bolt head sockets 23. Bolts 24 extend through the bolt sockets 23 of one gun unit and into the threaded sockets 22 of the adjacent gun unit, so that the several gun units are bolted together on opposite sides 5 of their respective cartridge bores. The bolts are preferably of the recessed head type.

Each gun unit is provided with a pair of conductor cable ports 25 which are centered with respect to the plane of the steps 4. These ports are provided with liners 26 of insulating material. The ports 25 of the several gun units register with each other so as to provide two continuous passages the length of the completed gun 10 perforator, formed by the gun units when they are stacked one on the other. Each conductor cable port, or passage thus formed, is adapted to receive a conductor cable 27 which carries a plurality of conductors 28. The cable 27 is provided, opposite each gun unit, with an annular channel 29 in which is fitted a terminal ring 30 connected with one of the conductors. The conductor tongue 19, from a corresponding gasket 18 and sealing plug 14, extends into the conductor cable port and engages the contact ring. The 15 marginal walls of the conductor cable 27 are relatively soft, but the cable, as a whole, is made stiff enough that it can be inserted down the two passages formed by the several conductor cable ports and past the several conductor tongues, so that 20 after the gun units have been assembled or stacked the conductor cables may be inserted to provide the proper electrical connections.

The lowermost gun unit is secured to a foot 35 piece 31 to facilitate guiding the tool into a well casing and the uppermost gun unit is secured to a head member 32, into which the cable extends. The head member 32 is suitably connected to a selector mechanism (not shown) which in turn is connected to an electric cable. 40 The selector mechanism may be in the nature of an ordinary selector or stepping switch for the purpose of connecting the several gun units in sequence through their respective conductors to a source of electrical energy. Such selector switch and supporting cable is, for the purposes of this application, conventional.

Various changes and alternate arrangements may be made within the scope of the appended 45 claims, in which it is my intention to claim all novelty inherent in the invention as broadly as the prior art permits.

I claim:

1. A gun perforator comprising: a plurality of gun units in the form of cylindrical disks having a greater diameter than thickness, said cylindrical disks being stacked axially, each gun unit having a laterally directed gun bore and an axially directed cartridge bore, each cartridge bore being covered by the adjacent gun unit; and 55 a means for securing said gun units together in a manner to withstand explosive pressures.

2. A gun perforator comprising: a plurality of gun units, each defining a radially directed gun bore and an axially directed cartridge bore intersecting an end of said gun unit, each gun unit forming a cover portion adapted to fit over and close the cartridge bore of an adjacent gun unit when said gun units are stacked.

3. A gun perforator comprising: a plurality of gun units, each being disk shape and adapted to be stacked end to end; means for securing said gun units in stacked relation; each gun unit having a laterally directed gun bore and an axially directed cartridge bore covered by the ad-

jacent gun unit; electrically responsive cartridges for said cartridge bores; and electrical conductors including leads clamped between said gun units and electrically connected with said cartridges.

4. A gun perforator comprising: a plurality of gun units, each being a short cylindrical section and having a breech portion of major thickness and a barrel portion of minor thickness, said gun units adapted to be stacked with their barrel portions and breech portions staggered; each gun unit having a cartridge socket in its breech portion and a gun bore extending diametrically therefrom through said barrel.

5. A gun perforator comprising: a plurality of gun units in the form of cylindrical blocks stacked to form a composite column; said blocks having complementary stepped axial ends restraining said blocks against relative lateral movement, and each block defining a laterally directed gun bore and an axially directed cartridge socket, said cartridge sockets being closed by confronting ends of the adjacent blocks.

6. A gun perforator comprising: a plurality of gun units in the form of cylindrical blocks stacked to form a composite column; said blocks having complementary stepped axial ends restraining said blocks against relative lateral movement, and each block defining a laterally directed gun bore and an axially directed cartridge socket, said cartridge sockets being closed by confronting ends of the adjacent blocks; electrically responsive cartridges for said sockets; and conductor means including leads interposed between said blocks and electrically connected with said cartridges.

7. A gun perforator comprising: a plurality of gun units in the form of cylindrical blocks stacked to form a composite column; said blocks having complementary stepped axial ends restraining said blocks against relative lateral movement, and each block defining a laterally directed gun bore and an axially directed cartridge socket, said cartridge sockets being closed by confronting ends of the adjacent blocks; electrically responsive cartridges for said sockets; said gun blocks defining a common axially extending passage; a conductor cable fitting said passage; and leads interposed between said blocks and making electrical connection between said cable and said cartridges.

8. A gun perforator comprising: a plurality of gun units, each being of disk shape and adapted to be stacked end to end; means for securing said gun units in stacked relation; each gun unit having a laterally directed gun bore and an axially directed cartridge bore covered by the adjacent gun unit; electrically responsive cartridges for said cartridge bores; conductor leads clamped between said gun units and electrically connected with said cartridges; said gun units defining a common axially extending passage; said leads extending into said passage; a conductor cable extending through said passage; and separable connector means for electrically connecting said cable with said leads.

9. A gun perforator comprising: a plurality of gun units in the form of blocks, each having an axially directed cartridge bore and a laterally directed gun bore, said blocks adapted to be stacked in such a manner that the cartridge socket of each gun unit is sandwiched between the gun bore defining portions of adjacent gun units and covered thereby; and means for securing said gun units together against explosive

pressures that may be generated in said cartridge sockets.

10. A gun perforator construction, as set forth in claim 9, wherein said gun units are thickened axially at their cartridge socket defining portions, and their gun bore defining portions are complementarily reduced in axial thickness.

11. A gun perforator comprising: a plurality of gun units in the form of blocks, each having an axially directed cartridge bore and a laterally directed gun bore, said blocks adapted to be stacked in such a manner that the cartridge socket of each gun unit is sandwiched between the gun bore defining portions of adjacent gun units and covered thereby; means for securing said gun units together against explosive pressures that may be generated in said cartridge sockets; said gun units defining a common axially extending passage; a conductor cable fitting said passage; leads interposed between said gun units and electrically connected with said cable; and electrically responsive cartridges in said cartridge sockets connected with said leads.

12. A gun perforator construction, as set forth in claim 9, wherein said gun units are thickened axially at their cartridge socket defining portions, and their gun bore defining portions are complementarily reduced in axial thickness; said gun units defining a common axially extending

passage; a conductor cable fitting said passage; leads interposed between said gun units and electrically connected with said cable; and electrically responsive cartridges in said cartridge sockets connected with said leads.

13. A gun perforator comprising: a plurality of gun units, each defining a radially directed gun bore and an axially directed cartridge bore intersecting one end of said gun unit, said gun units adapted to be stacked with the side of one gun unit closing the cartridge bore of the adjacent gun unit; and axially directed securing means extending between adjacent gun units on either side of said cartridge bores to hold said gun units in sealing relation.

14. A gun perforator comprising: a plurality of gun units, each defining a radially directed gun bore and an axially directed cartridge bore intersecting one end of said gun unit, said gun units adapted to be stacked with the side of one gun unit closing the cartridge bore of the adjacent gun unit; said gun units directed alternately in opposite directions, the gun bore of each being between the cartridge bore of the adjacent gun unit; and tie bolts on opposite sides of the gun bore of each gun unit extending therefrom into an adjacent gun unit on opposite sides of the cartridge bore of said adjacent gun unit.

LLOYD SPENCER.
